UNITED STATES PATENT OFFICE.

OTTO KNOERZER, OF HAMMOND, INDIANA.

DESIGN FOR A GARAGE-EMBLEM.

41,485.

Specification for Design. Patented June 20, 1911.

Application filed December 19, 1910. Serial No. 598,218. Term of patent 7 years.

To all whom it may concern:

Be it known that I, OTTO KNOERZER, a citizen of the United States, residing at Hammond, in the county of Lake and State of Indiana, have invented a new, original, and ornamental Design for Garage-Emblems, of which the following is a specification, reference being had to the accompanying drawing, forming part thereof.

In the drawing Figure 1 is a side eleva-

tion of a garage-emblem, showing my design. Fig. 2 is an end view thereof.

I claim—

The ornamental design for a garage-emblem as shown.

OTTO KNOERZER.
